BURT R. SIMMONS, OF PALMS, CALIFORNIA.

SHOCK-PREVENTING DEVICE FOR RAILWAY-CROSSINGS.

1,279,028.

Specification of Letters Patent. Patented Sept. 17, 1918.

Application filed September 27, 1917. Serial No. 193,484.

To all whom it may concern:

Be it known that I, BURT R. SIMMONS, a citizen of the United States, residing at Palms, in the county of Los Angeles and 5 State of California, have invented new and useful Improvements in Shock-Preventing Devices for Railway-Crossings, of which the following is a specification.

This invention relates to a railway crossing and particularly pertains to a shock preventing device therefor.

The principal object of this invention is to provide a railway intersection with a hydraulically operated mechanism controlled 15 by the movement of car wheels along the tracks to selectively continue the rails across the intersection so that there will be no violent jar as the wheels pass thereover.

Other objects will appear hereinafter.

20 The invention is illustrated, by way of example, in the accompanying drawings in which:

Figure 1 is a fragmentary view in plan illustrating a railway intersection, the tracks 25 of which are provided with the shock preventing mechanism with which the present invention is concerned.

Fig. 2 is a view in vertical section drawn upon a reduced scale illustrating in a dia- 30 grammatical manner the compression mechanism of the device during the down stroke of its piston.

Fig. 3 is a view similar to Fig. 2 illustrating the device during the up stroke of the 35 piston.

Fig. 4 is a view similar to the two preceding views illustrating the final positions of the valves within the compression mechanism during the final stage of the up stroke 40 of the piston.

Fig. 5 is a view in vertical section on the line 5—5 of Fig. 1 illustrating the yieldable mounting of the compression bars in relation to the side of the track.

45 Fig. 6 is an enlarged view in vertical section and elevation illustrating one unit of the complete device, particularly disclosing the arrangement of the vital parts of the compression and expansion members.

50 Referring more particularly to the drawings, 10 and 11 indicate parallel rails forming a track —A—, while 12 and 13 indicate parallel rails of a track —B—. As shown, the tracks —A— and —B— intersect each 55 other at right angles. The rails previously designated are continued across the intersec-

tion by filler rails 10' 11', 12' and 13' which form continuations of the rails 10—13 respectively. The filler rails are shorter than the intervening spaces between the main rails 60 and thus form flange grooves along which the flanges of car wheels may pass. These grooves are adapted to be filled by filler blocks, eight of which are used. The spaces at the opposite ends of the filler rail 10' may 65 be filled by blocks 14 and 15, while the spaces at the opposite ends of the rail 11' may be filled by blocks 16 and 17. The spaces at the opposite ends of the rails 12' and 13' may be filled with blocks 18 and 19, and 20 70 and 21, respectively. All of the blocks are rectangular in plan and may be vertically actuated by a mechanism with which the present invention is particularly concerned. During said actuation the blocks will be 75 divided into two sets, one set for the track —A—, comprising blocks 14—17 inclusive, and another set for the track —B—, comprising the blocks 18—21 inclusive. These sets are indirectly actuated by the wheels as they 80 encounter compression bars 22 and 23, and 24 and 25, the bars 22 and 23 being disposed in the flange groove of the rail 11 of track —A— and upon opposite sides of the intersection while the bars 24 and 25 are disposed 85 within the flange groove of rail 13 of the track —B— and at opposite sides of the intersection.

The compression bars are shown in detail in Fig. 6 of the drawing where it will be seen that they extend horizontally along a rail of each track and are supported by bolts 26 and 27 which extend through parallel slotted openings 28 and 29 in the bars and secure them for vertical movement to the sides of 90 the rails. The bars may be of any desired length and are here shown as being approximately two feet long and as being beveled at their opposite ends to allow the flanges of car wheels to readily ride upon the bars 95 and depress them.

The bars 22—25 inclusive are mounted above compression mechanisms 30—33, respectively, one of which is shown in detail in Fig. 6. In this view it will be seen that 100 each of the bars is fitted with a downwardly extending stem 34 which projects into a bore of a piston rod 35. The stems have enlarged head portions upon which the bars rest and may have horizontal sliding move- 110 ment. This rod is vertically disposed and is fitted with a collar 36 upon which a helical

expansion spring 37 is positioned. This spring directly supports one of the bars. The piston rod extends downwardly through a packing gland 38 in the cover casting 39 of a reservoir 40. The reservoir has an integral lower end wall 41 through which the rod extends and around which a packing box 42 is positioned. Interposed between the collar 36 and the cover casting 39 is a 5 large compression spring 43 which combines its action with the smaller spring 37 above the collar for a purpose which will be hereinafter set forth. Secured to the lower end of the piston rod is a piston head 44. An 10 annular facing 45, preferably formed of cast iron, is secured around the peripheral edge of the piston head 44 and is formed with grooves within which piston rings 46 are placed. The piston so formed is reciprocally 15 mounted within a cylinder 47 of a compression chamber 48, the chamber and cylinder being cast integral and bolted beneath the reservoir 40, the bottom wall 41 of said reservoir acting as a closure for the 20 compression chamber.

Communication may be established between the reservoir 40 and the compression chamber 48 through three openings, a relief valve opening 49 in direct communication 25 with the main portion of the compression chamber, a suction valve opening 50 in direct communication with the upper end of the cylinder 47 and above the piston 44, and a return by-pass 51 in communication with 30 the cylinder 47 above the piston. The relief valve opening 49 is formed with a tapered valve seat around its lower edge against which a relief valve 52 will normally be seated. This valve is fitted with a vertically 35 extending stem 53 which passes through a bearing 54 supported by a spider cast across the opening. A collar 55 is disposed at the upper end of the stem 53 and held by a nut 56. Interposed between the collar and 40 the bearing 54 is a helical expansion spring 57 which normally acts in a positive manner to hold the valve 52 upon its seat. The suction valve opening 50 is also formed with a tapered valve seat around its lower edge 45 against which a suction valve 58 is normally seated. This valve is formed with an upwardly extending vertical stem 59 which passes through a bearing spider 60 and is supported by an expansion spring 61 interposed 50 between the bearing and a collar 62 secured at the outer end of the stem. The by-pass opening 51 is threaded to receive a by-pass plug 63 which extends vertically 55 into the reservoir 40 and is formed with a by-pass 64 which leads from the upper end of the cylinder 47 and into the reservoir. A needle valve 65 regulates the flow of liquid 60 from the cylinder 47 through this by-pass. It will be seen that the stem of the needle ex- 65 tends upwardly through a packing gland 66

in the cover 39 and is there formed with a head 67 by which the stem may be rotated. It will be understood that the stem is threaded and mounted within the threaded bore of the by-pass plug 63.

The lower end of the compression chamber 48 is formed with a master valve opening 68. This opening is formed with a tapered seat around its lower edge adapted to receive a master valve 69. It is to be understood that the valves 52, 58 and 59 are all of the puppet valve type and are each disposed with their stems extending upwardly and their valve heads inverted. This master valve is formed with a tubular 70 stem 70 mounted through a bearing 71. The upper end of this stem is threaded to receive a collar 72 and between this collar and the bearing is interposed a compression spring 73 which normally draws the valve 80 upwardly against its seat and in opposition to the weight and compression of an incompressible fluid with which both the reservoir and compression chamber are filled.

The tubular stem 70 of the master valve 90 69 is provided to receive a balance valve stem 74 upon the lower end of which is formed a pair of opposed balanced valve members 75 and 76. These members are spaced from each other along the stem and 95 simultaneously bear upon separate valve seats formed in a valve cage at the bottom of the valve member 69 and integral therewith. A screw-cap 77 is fastened over the lower end of this cage to support an expansion spring 78 which bears against the lower one 76 of the valve members and holds the valve members 75 and 76 upon their seats. A valve chamber 79 is formed in the valve 100 cage and at the opposite ends of this chamber are the valve seats for the valve members 75 and 76. An inlet opening 80 is formed through the side of the cage and in communication with the chamber 79. The upper valve member 75 normally closes a pair of 105 by-pass ducts 61 and 62 which provide communication between the chamber 79 and the compression chamber 48 when the valve member 75 is in its lowermost position. A long by-pass duct 83 extends downwardly 110 along the wall of the valve cage and establishes communication between the cavity in the cap 77 of the cage and the compression chamber 48, thus allowing communication to be established between the valve chamber 115 79 and the compression chamber when the lower valve member 76 is down. It will be understood that the surface areas of the valve members 75 and 76 as exposed within the chamber 79 are equal and that the pressure 120 of an incompressible liquid will hold the valve in balance.

Mechanical means is provided for actuating the relief valve, the master valve 69, and the balance valve composed of the valve 125

members 75 and 76. This mechanism consists of a rocker lever 84 which is pivotally mounted upon a pivot pin 85 extending across the compression chamber to pivotally support the lever for vertical swinging movement. The pivot pin is disposed at a point intermediate the ends of the lever and permits the lever to be actuated indirectly by the movement of the piston 44 and its rod.

10 The end —*a*— of the lever extends into a fork 86 secured beneath the piston head and as a continuation of the piston rod 35.

Interposed between the forked ends of the extension is a trip dog 87 which is mounted upon a pivot pin 88. This dog is formed with two fingers, a tripping finger 89 adapted to engage a projection 90 upon the side of the compression chamber 45, and an actuating finger 91 which at certain times during the movement of the piston may strike the lower face of the end —*a*— of lever 84 to swing it upon its pivotal center. This dog is also provided with a counterweight 92 disposed upon the opposite side of its pivotal center and normally acting against the projection 90. The opposite end —*b*— of the lever 84 is provided with a pin 93 which projects into a vertically disposed elongated slot 94 formed through a connecting shackle 95 secured rigidly to the lower face of the relief valve member 52. As normally disposed, the pin 93 seats at the lower end of the slot and thus will permit the valve member 52 to have a downward motion without restriction by the pin 93 or its lever.

The master valve opening 68 is surrounded by a downwardly extending sleeve 96 within which a pipe elbow 97 is fastened. This elbow is connected with a main pressure pipe 98 which extends parallel to the rail under which the compression mechanism is mounted, beneath and across the intersecting track, and to the other compression mechanism along the same rail. In this manner the compression mechanisms 30 and 31 will be connected by the pipe 98, and the compression mechanisms 32 and 33 by a similar pipe 98'. A pipe $\mathbf{T}$ 99 is interposed mid-way the length of the pipe 98 and in communication therewith. This $\mathbf{T}$ is also in communication with a secondary supply pipe 100 extending parallel to the pipe 98 and connected with expansion mechanisms 101 and 102 at its opposite ends. The mechanisms 101 and 102 are beneath the filler blocks 16 and 17 and are provided to vertically reciprocate them in a manner which will be hereinafter described. The filler blocks 14 and 15 are provided with expansion mechanisms 103 and 104 which are in communication with each other through the medium of a secondary supply pipe 105. This pipe is connected with the secondary supply pipe 100 by a connecting pipe 106, thus allowing a fluid under pressure to simultaneously

pass from the pipe 98 into the auxiliary pipes 100 and 105 and each of the expansion mechanisms 101-104 inclusive. It will be understood that the pipe 98' is in communication with auxiliary supply pipes 100' and 105' and the connecting pipe 106' which supplies a noncompressible fluid to expansion mechanisms 107-110 inclusive.

One of the expansion mechanisms is shown in Fig. 6 and has a vertically disposed cylinder 111 within which a piston 112 is mounted. This piston is normally held at the bottom of the cylinder by a helical expansion spring 113 which is inclosed within the cylinder and interposed between the upper end 114 of the cylinder and a collar 115 forming a part of the piston rod 116 at the lower end of which the piston is fastened. Mounted upon the upper ends of the piston rods 116 are the filler blocks 14-21 inclusive. 85 These blocks are directly connected with these piston rods and are reciprocated as a noncompressible fluid is delivered from the compression mechanisms to the expansion mechanisms.

In operation, the railway crossing is assembled as shown in Fig. 1 and supplied with the compression mechanisms 30-33 inclusive and the expansion mechanisms 101-104 inclusive and 107 to 110 inclusive. 95 The compression mechanisms are normally disposed with their parts in relation to each other as shown in Fig. 6 and the expansion mechanisms as shown in the same figure. When the truck of a car passes along one 100 of the tracks and approaches the intersection, a forward wheel of the truck will encounter one of the compression bars along the track, as indicated by the numerals 22, 23, 24 and 25. The flange of the wheel will 105 bear down upon this bar and move it in the direction of the arrow —*c*— as shown in Fig. 6. This will cause the stem 34 of the bar to telescope within the upper end of piston rod 35 of one of the compression mechanisms. 110 During this movement the expansion spring 37 will be compressed to allow the compression bar to move to an unobstructing position along the side of the track. After the expansion spring 37 has been entirely compressed, it will act upon the collar 36 to move piston rod 35 downwardly against the action of the large compression spring 43. As the piston rod moves downwardly it will force the piston 44 downwardly within the 115 cylinder 47. This movement of the piston will create a suction in the cylinder 47 and above the piston, drawing the suction valve 58 downwardly and drawing the incompressible fluid from the reservoir 40. At the same time, force will be exerted by the piston upon the incompressible fluid within the chamber 48 which will force the master valve 120 downwardly from its seat and cause the incompressible fluid to travel along the various 125 130

conduits to the complementary expansion mechanisms connected therewith. In the present description it will be assumed that the compression mechanism 33 has been actuated. This will simultaneously force the incompressible fluid into the cylinders of expansion mechanisms 107, 108, 109 and 110. During this stage of the operation, the suction valve 58 and the master valve 69 will be in the positions shown in Fig. 2 of the drawings, at which time the pistons 112 within the expansion cylinders 111 will be acted against to raise piston rods 116 upwardly against the action of the springs 113 and raise the filler blocks. In the present case blocks 18-21 inclusive will be affected. The complementary compression mechanism 32 will not be effected, due to the fact that the ends of the compression bars adjacent the intersection of the tracks are beveled to allow the flange of the wheel to wedge between the bar and the rail and force the bar outwardly from the rail and against the compression of springs 117 which are mounted upon the bolts 26 and 27 of each bar, as particularly shown in Fig. 5.

The compression bar connected with the actuated compression mechanism 33 will not be immediately restored to its original position by the expansive action of springs 37 and 43 but will gradually move to this position during a predetermined interval of time. The speed of movement of the compression bars to their original position will be regulated by the flow of the incompressible liquid from the cylinder 47 through the by-pass opening 64 to the reservoir 40, the needle valve 65 being adjusted to regulate this flow and thus to allow the piston 44 to rise to the top of the cylinder 47 under the influence of the expansion spring 43. As the piston moves upwardly, the pressure in the piping system produced by the expansion springs 113 will act to force the master valve 69 against its seat and at the same time the piston will draw the relief valve 52 from its seat, as particularly shown in Fig. 3. This will allow the fluid from the reservoir to pass into the chamber 48 and occupy the displacement space caused by the upward movement of the piston 44 within the cylinder 47. It will be understood that the independent action of the relief valve 52 is possible due to the loose connection between the valve shackle and the lever 84. As the piston continues to move upwardly, the actuating finger 91 of the dog 87 will strike the lower face of the end —a— of lever 84. This finger has been held in this position by lug 84' which extends outwardly from the extension 86 of the piston rod to limit the downward movement of the counterweight. The engagement of the finger with the lever takes place when the piston is almost at the end of its upward stroke and

will cause the relief valve 52 to be positively drawn down to permit a larger volume of fluid to pass from the reservoir than did pass when the relief valve 52 was partially opened by suction. At the same time the relief valve is forcefully drawn down, the end —b— of the lever 84 will strike the stem 74 of the balanced valve and then strike the stem 70 of the master valve, thus breaking the seal of the master valve and then opening it to allow the incompressible liquid to pass into the chamber 48 from the expansion mechanisms which had previously been effected thereby. At this instant, the relief valve 52 and the master valve 69 will both be opened, as shown in Fig. 4, and, as will be understood, a complete equalization of the pressure and volume of incompressible fluid will be effected in the compression chamber 48 and the reservoir 40, as well as within the pipe system leading to the expansion mechanisms. During this time the piston is still moving to its uppermost position and the trip finger 89 of the dog 87 has engaged the projection 90 upon the side wall of the compression chamber. As the piston reaches the upper end of its stroke the engagement of these two members will cause the actuating finger 91 to swing downwardly from beneath the end —a— of lever 84 and consequently allow the end —b— of the lever to swing upwardly to relieve the lever pressure from the lower valve stems 70 and 74 and tension from the relief valve shackle 95. It will be understood that the end —a— of lever 84 is heavier than the end —b— and will normally hold the end —b— in its uppermost position and out of operative engagement with the valve shackle 95 and the valve stems 70 and 74. When the piston reaches its uppermost position, the incompressible fluid will be restored to the reservoir 40 and the compression chamber 48 as before the car wheel actuated the compression bar, the relief valve 52, the suction valve 58, the master valve 69, and the balanced valve members 75 and 76 will all be seated, and the mechanism will be in condition for further operation.

As the compression bar is slow in being restored to its original position, the filler blocks indirectly effected thereby will be held in their uppermost position an interval of time predetermined by the adjustment of the needle valve 65 in relation to the by-pass bore 64. This will be quite convenient when a train of cars is passing along the track. In case, however, the bar is slightly or entirely raised, the small expansion spring 37 will allow it to be easily depressed without violent shock to the bar.

It will thus be seen that the crossing apparatus here disclosed may be easily set up for operation and will operate in a positive automatic manner to form continuous rails

for the wheels of an approaching car, irrespective of the direction from which the car is coming or upon which of the tracks it is traveling.

5 While I have shown the preferred construction of my shock preventing device for railway crossings as now known to me, it will be understood that various changes in the combination, construction and arrangement of parts may be made by those skilled in the art without departing from the spirit of my invention as claimed.

I claim:

1. In an apparatus of the character described, the combination with a railway crossing, of a series of tread members located adjacent the intersecting rails thereof, a cylinder associated with each tread member, a piston in each cylinder, a hydraulic reservoir connected to said cylinders, and means carried by said reservoir operative to force a liquid therefrom to actuate the pistons in said cylinders.

2. In an apparatus of the character described, the combination with a railway crossing, of a series of tread members located adjacent the intersecting rails thereof, a cylinder associated with each tread member, a piston in each cylinder, a hydraulic reservoir connected to said cylinders, means carried by said reservoir and operative to force a liquid therefrom to actuate the pistons in said cylinders, means for returning the last-named means to its normal position, and means for regulating said return movement.

3. In an apparatus of the character described, the combination with a railway crossing, of a series of tread members located adjacent the intersecting rails thereof, a cylinder associated with each tread member, a piston in each cylinder, a hydraulic reservoir connected to said cylinders, means carried by said reservoir and operative to force a liquid therefrom to actuate the pistons in said cylinders, means for returning the last-named means to its normal position, and means actuatable by said returning movement to permit of the return of the liquid into said reservoir.

4. In an apparatus of the character described, the combination with a railway crossing, of a series of tread members located

adjacent the intersecting rails thereof, a cylinder associated with each tread member, a piston in each cylinder, a hydraulic reservoir connected to said cylinders, means carried by said reservoir and operative to force a liquid therefrom to actuate the pistons in said cylinders, and means for automatically returning the last-named means to its normal position.

5. In an apparatus of the character described, the combination with a railway crossing, of a plurality of tread members located adjacent the intersecting rails thereof, pistons associated with said tread members, a cylinder for each of said pistons, main and branch feed pipes connected to said cylinders, a sectional reservoir connected to said main feed pipe, a valve for controlling said connection, a depressible piston located in the lower section of said reservoir and adapted to force the liquid therefrom into the feed pipe for raising the first-named pistons, means for permitting the passage of a fluid from the upper section of said reservoir into the space above the piston therein when the latter is lowered, and means for returning the piston to its normal position.

6. In an apparatus of the character described, the combination with a railway crossing, of a plurality of tread members located adjacent the intersecting rails thereof, pistons associated with said tread members, a cylinder for each of said pistons, main and branch feed pipes connected to said cylinders, a sectional reservoir connected to said main feed pipe, a valve for controlling said connection, a depressible piston located in the lower section of said reservoir and adapted to force the liquid therefrom into the feed pipe for raising the first-named pistons, means for permitting the passage of a fluid from the upper section of said reservoir into the space above the piston therein when the latter is lowered, means for returning the piston to its normal position, means for controlling the return of said piston, means operated by the return of said piston to open said valve to permit of the inflow of fluid into the lower section of the reservoir, and means for again closing said valve.

In testimony whereof I have signed my name to this specification.

BURT R. SIMMONS.
